UNITED STATES PATENT OFFICE.

DAVID S. RING, OF WALTHAM, MASSACHUSETTS.

METHOD OF MAKING BRUSHES.

1,244,132.

Specification of Letters Patent. Patented Oct. 23, 1917.

Application filed December 19, 1912. Serial No. 737,615.

To all whom it may concern:

Be it known that I, DAVID S. RING, a citizen of the United States, and resident of Waltham, in the county of Middlesex and 5 State of Massachusetts, have invented certain new and useful Improvements in Methods of Making Brushes, of which the following is a specification.

My invention consists in a new mode of 10 fastening bristles or other brush material in the holders, handles, or backings of brushes, by which the bristles are securely held, and are secured without the use of adhesives and without the necessity of applying heat. In the accompanying drawings.

Figure 1 represents an elevation and

Fig. 2 a sectional plan view on line 2—2 of Fig. 1; of one possible embodiment of 20 means for carrying out my invention.

Figs. 3 to 7 inclusive illustrate the steps of the method in which the invention resides.

Fig. 8 is a fragmentary view of a portion 25 of a brush made in accordance with the invention and embodying another aspect of the invention.

Fig. 9 is a view illustrating a further step 30 in addition to those illustrated in the foregoing figures, by which a modified structure of brush is produced and

Fig. 10 illustrates the brush produced by this further step.

Fig. 11 is a detail view of a part of the 35 apparatus, being a section taken on line 11—11 of Fig. 2.

The same reference characters indicate the same parts in all the figures.

The invention does not depend for its carrying out upon the use of any particular 40 machine, but may be performed by hand manipulation, with the employment of suitable tools. However, in order to obtain the best results and to apply the great pressures necessary to secure the brush material by friction in the holder, I find it desirable to employ some sort of press and mechanism for sustaining the parts of the brush and the operating implements in proper alignment. In Figs. 1 and 2, I have shown a suitable apparatus which I may employ in carrying out the method, but this apparatus is shown for illustration only and any other having certain characteristics hereinafter named may be used. In Figs. 1 and 2, 10 50 55 represents the table or base of a press and

11 represents the plunger or ram of the press. Any sort of press operated in any known manner may be used, provided it is capable of furnishing sufficient pressure. 12 represents the base of a holder and guide 60 for the implements used in carrying out the process, which holder has an upright 13 carrying an overhanging head 14 which provides a guide and has a bushing 15 in which certain implements are guided. The holder 65 rests on the table of the press and is preferably so attached, as by a pivot 16, that it may swing out from under the plunger 11 and back again. This pivot and a stop 17 are provided merely to allow the holder to 70 be placed properly after having been displaced, without loss of time. In the base is a guideway 18 in which are mounted sliding clamps 19, 20; one of which abuts against an adjustable abutment screw 21 threaded 75 through the upright 13. A cam 24 is mounted adjacent the end of the other clamp and is connected with an operating lever 25. In their adjacent ends clamps 19 and 20 have recesses 26 which together form a socket of 80 a shape and size to fit around the brush holder ferrules hereinafter described and to clamp the ferrules. Through the base 12 of the holder is a passage 27 and through the table of the press is a passage 28, these passages being in line beneath the socket formed as above stated between the clamps 19 and 20. Crossing the base 12 beneath the abutting ends of the clamps is a slide 29 having an aperture 30 which may be placed beneath the socket recesses 26 or at one side thereof as shown in Fig. 11.

I will now describe the process in the use of which I employ the apparatus above described. I take a ferrule 31 which is a complete ring or band of any desired outline, but usually circular, which has previously been filled with bristles 32 or the like brush material, by hand or otherwise, as full as possible. It is not important what the character of the ferrule is or what its shape, provided only it is a complete band without divisions, and sufficiently strong to confine the bristles at completion of the brush. This ferrule, thus filled, is placed between the 105 clamps 19 and 20 which have been separated and is allowed to rest on the plate or slide 29, which latter is then in the position shown in Fig. 11 with the aperture 30 displaced from the opening between the clamps: 110

Clamp 19 is adjusted by the abutment screw 21 until its socket is in the proper alinement with the guide 15, and then the clamp 20 is closed against it by the lever 25 and cam 24. No great amount of pressure need be exerted by this clamp more than enough simply to grip the ferrule 31 firmly and prevent its displacement in the further steps of the process. The bristles are then held at their butt ends only by the ferrule and project upwardly therefrom as shown in Fig. 3. The next step is to open a passage in the interior of the mass of bristles and insert a guide therein. The guide is a tube 33 which is adapted to slide endwise through the head 14 and the bushing 15. For convenience of manipulation, as will be later explained, this tube is not continuous but is made in two parts connected by an open frame 34 as shown in Fig. 1. Inside of the guide tube 33 is a plunger 35, which may be solid or tubular as desired, provided only it has a socket in its lower end of sufficient size to receive the shank of a spreader 36. Such spreader is preferably made as a comparatively blunt cone, adapted to fit slidingly in the guide tube 33 and having a shank 37 which projects into the end socket of the plunger 35 and is secured in any suitable way, as by a bayonet joint fastening provided by a pin 38 on the shank entering an angle slot 39 in the plunger. The plunger and guide tube are lowered together from the position shown in Fig. 3 to approximately that shown in Fig. 4, the conical spreader opening a passage through the bristles and the guide tube following through the passage. Preferably the end of the guide tube is beveled as shown at 40 in Fig. 3 so as to make a continuation of the conical surface of the spreader and avoid any abrupt shoulder which might catch the ends of some of the bristles and bend them. When the spreader and guide tube have advanced as far as they can under moderate pressure, a clamp or binder is applied outside of the bristles. Such clamp consists of jaws 41 pivoted together either directly or by links 42, 43. The jaws and links are recessed so as collectively to fit around the mass of bristles as shown best in Fig. 2. The outer faces of the jaws are divergent from their ends inwardly and are engaged by a strap 44 which is forced over them until they bind the bristles tightly against the tube 33. Preferably the clamp is of such width as to embrace the bristles throughout nearly their entire length as shown in Figs. 4, 5, 6, and 7. The particular construction of the clamp is not an essential element of the invention, provided only it is so made as to bind the bristles with approximately uniform force about all sides of the guide tube. The plunger with the spreader is then withdrawn, leaving the guide tube held

firmly in place by the clamp in the midst of the bunch of bristles.

The spreader point is now removed from the plunger and a sharper pointed instrument 45, which I may call the "packing" instrument is substituted. In making this substitution the open frame 34 is of service, because it gives the operator access to the plunger end without requiring the plunger to be entirely withdrawn from the upper end of the guide tube. That is, in order to make this substitution it is necessary to lift the plunger through a distance not much greater than the length of the brush. The packing instrument has a shank which fits in the end socket of the plunger and is secured frictionally, or if necessary positively, by any means such as that for holding the spreader. The packing instrument also has a portion 46 of greater diameter than the shank bounded at one end by a shoulder 47 which abuts on the end of the plunger and at the other end by a larger shoulder 48. This portion 46 is adapted to receive an inner ferrule or binder 49 which has substantially the same axial extent as the outer ferrule 31 and is of such diameter that it may pass through the guide tube 33. The binding ferrule 49 is first slipped on the packing tool and then the shank of the latter is inserted in the plunger. Then the device is moved under the ram of the press, and the latter comes against the upper end of the plunger. Before actuating the ram, however, the slide 29 is drawn out until the aperture 30 therein comes under the brush. Now pressure is exerted by the ram and the finely tapered spreader is forced down through the guide tube and through the bottom of the brush until the inner ferrule is in the zone 105 of the outer ferrule as shown in Fig. 6. The pressure is then relieved, the sharp pointed packer withdrawn through the bottom of the press, the clamp 41 released and the guide tube 33 retracted. The essential part 110 of my process is now complete, as the bristles are now attached to a holder which is capable of being applied to any sort of a brush handle or back. When the inner or binding ferrule has been brought into the position 115 shown in Figs. 6 and 7, it is so firmly bound there by the pressure of the compacted annular layer of bristles, that it cannot be removed except with the greatest difficulty. As the bristles, when loosely filling the outer ferrule are quite closely packed, it is evident that great force is required to compress them into the greatly restricted annular area between the inner and outer ferrules. The force thus expended compacts the bristle butts into a mass as firm and hard almost as compressed fiber, and this energy is stored up and exerted on the inner ferrule, holding the latter in place. Thus the bristles are bound in place by the two ferrules 125 130.

and the inner ferrule is secured by the outer ferrule and the mass of bristles. These parts now make a unitary structure which will not fall apart, but is firmly united, and in which the bristles are so firmly held that when pulled upon they will break before they will come out from the ferrules. These ferrules may be placed in an annular thimble 50, as shown in Fig. 8, which is set into a shell 51 forming the handle of a magazine shaving brush or of any other kind of brush, or they may otherwise be connected with a brush handle or back.

A mode of further treating the brush unit, which term I use to designate the unit composed of the ferrules or bands and the bristles, is shown in Fig. 9. Here the unit is placed on the bed 52 of another press and a guide rod 53 is passed through the unit to open the channel in the midst of the bristles. A plug 54 somewhat tapered on its exterior is placed on the end of the guide rod, and a plunger 56 is actuated by severe pressure to force the plug into the inner ferrule, the guide rod at this time withdrawing as fast as the plug is advanced. The guide rod has a teat 57 which enters a passage through the plug and centers the latter. As the larger end of the plug is somewhat greater than the internal diameter of the ferrule, it crowds the latter outward, reinforces it and strengthens the bind upon the bristles. It also provides a means by which the brush unit may be attached to a handle or back, for its central passage allows a screw or other fastening 58 to be passed through into a handle.

It is to be particularly noted that my improved method results in a brush wherein the bristles are held by friction between two mechanical binding or retaining elements, and not by any other means or agent. In particular I desire to state that I do not employ rosin, glue or any gum or adhesive to secure the bristles. I also wish it noted that I do not require the agency of heat, which must be employed where bristles are set in vulcanized rubber, and which frequently injures the bristles. On the contrary in my brush the bristles are secured without any heating above the temperature of the work place and are therefore not injured in the least. There is practically no limit to the amount of pressure which may be employed by the means of guide shown in gripping the bristles, because the press and holder may be made strong enough to withstand any concentrated pressure. At the same time the pressure employed does not injure the bristles or weaken them at all, but simply holds them more firmly in proportion to its force. The inner and outer bands or ferrules are both continuous and

endless and grip the bristles with substantially equal force at all points, and, owing to the manner in which they are assembled, the density of the mass of bristles between any contiguous points on both ferrules is uniform.

I claim:

1. The method of making a brush which consists in placing the ends of a mass of brush material in an outer binder, inserting a tubular guide in the midst of the brush material, clamping the brush material about said guide, passing a packing implement and an inner binder through the guide and the material while so clamped, and leaving the inner binder within that portion of the mass of brush material which is surrounded by the outer binder.

2. The method of making a brush which consists in placing one end of a collection of bristles in an outer binder, inserting a tubular guide into the center of the mass of bristles from the tips thereof toward the binder, at the same time spreading the bristles so that they lie outside of said guide, passing a tapered packer successively through the guide and the outer binder, so as to spread and pack the butts of the bristles against the outer binder, inserting an inner binder in the space opened by said packer, and withdrawing the guide.

3. The method of forming a brush which consists in placing one end of a mass of brush material in an annular outer binder, inserting a tubular guide in the center of that portion of the brush material which projects from the binder, at the same time spreading the material so that it surrounds the guide and leaves the interior of the guide open, placing a clamp around the brush material and gripping the same against the guide, passing an inner binder through the guide and into the zone surrounded by the outer binder, and finally removing the clamp and guide.

4. The method of making a brush which consists in placing an annular binder or ferrule about the end of a mass of bristles, opening the center of that part of the mass projecting from said binder and inserting a tubular guide in the space thereby formed in the mass, forcing a tapered packer and an inner binder together through the guide and through that portion of the mass which is surrounded by the outer binder, removing the packer, and removing the guide.

In testimony whereof I have affixed my signature, in presence of two witnesses.

DAVID S. RING.
